UNITED STATES PATENT OFFICE.

JOHN O'CALLAHAN, OF PHILADELPHIA, PENNSYLVANIA.

DESIGN FOR A BADGE.

SPECIFICATION forming part of Design No. 35,927, dated May 27, 1902.

Application filed April 18, 1902. Serial No. 103,661. Term of patent 7 years.

To all whom it may concern:

Be it known that I, JOHN O'CALLAHAN, a citizen of the United States, residing at Philadelphia, in the county of Philadelphia and 5 State of Pennsylvania, have invented and produced a certain new and useful Design for Badges; and I do hereby declare the following to be a full, clear, and exact description of the invention, such as will enable others skilled in the art to which it appertains to make and use the same.

My invention relates to a new and useful design for badges, of which the following is a specification, reference being had to the accompanying drawing, forming a part thereof, in which the figure is a plan view of my design.

As shown in the drawing, the leading or material features of my design are two concentric circles 1 and 2, which are partially surrounded by two sprays 3 of shamrock, the

inner circle 2 containing two flags, an American flag 4 and an Irish flag 5, the latter comprising a harp 6 in a plain field. Located below the said circles is a field surrounded by 25 a heart-shaped border 7, and contained in said field is an Irish harp 8, partially surrounded by a spray of shamrock 9.

The above-stated features of my design are formed on a ribbon 10, which is attached by 30 a pin 11.

Having described my invention, what I claim as new, and desire to secure by Letters Patent, is—

The design for a badge, substantially as 35 shown and described.

In testimony whereof I affix my signature in presence of two witnesses.

JOHN O'CALLAHAN.

Witnesses:

ALBERT DE UNGER,
JOHN J. DEAN.
